HARRY G. HOFFMANN AND GENEVIEVE B. HOFFMANN, OF OAKLAND, CALIFORNIA.

HAIR WAVER.

Application filed June 16, 1920. Serial No. 389,274.

To all whom it may concern:

Be it known that we, HARRY G. HOFFMANN and GENEVIEVE B. HOFFMANN, citizens of the United States, and residents of Oakland, 5 county of Alameda, and State of California, have invented a new and useful Hair Waver, of which the following is a specification.

Our invention relates to devices for producing an artificial curl or wave to the hair. 10 An object of the invention is to provide a flexible hair waver which may be folded upon itself and made to firmly retain the hair when wound thereon without the aid of a catch yet which may be readily unfolded 15 and caused to assume an extended position without having a kink formed therein after the waver has been used a number of times.

The invention possesses other objects and features of advantage, some of which, with 20 the foregoing, will be set forth in the following description of the preferred form of our invention which is illustrated in the drawings accompanying and forming part of the specification. It is to be understood that we 25 do not limit ourselves to the showing made by the said drawings and description, as we may adopt variations of the preferred form within the scope of our invention as set forth in the claims.

30 Referring to said drawings:

Fig. 1 is a perspective view of the waver in its extended or inoperative position, portions of the covering being removed to disclose the interior members more clearly.

35 Fig. 2 is a side elevation of the waver in its folded position showing the hair engaged therein.

Fig. 3 is a perspective view of a modified construction of the waver.

40 The waver comprises a plurality of wire units 2, 3 and 4, twisted or woven together, or as here shown formed into a braid. In the present embodiment of the invention three wire units are used, each one of which 45 is composed of a plurality of strands 5 and 6. The wires 2, 3 and 4 are each preferably provided with a protective covering 7 of some textile fabric or the like and if de-

sired the braid as a whole may be wrapped in a suitable covering 8 as shown in Fig. 3. 50

As clearly seen in Fig. 1 the strands 5 and 6 of each wire are preferably aligned cross-wise with respect to the width of the waver, so that a flat braid is formed whose thickness is not much more than that of two 55 strands.

The adjacent ends of the wires and their strands are preferably secured by caps 9 and 10 thereby lending firmness to the entire structure. 60

When it is desired to use the waver the hair is wound upon one end as shown in Fig. 2 and the waver is then bent or folded upon itself to firmly retain the hair thereon. After the hair has been held in the waver a 65 suitable length of time, the waver may be unfolded to an open or extended position so that the waved hair can be readily disengaged therefrom. Due to the peculiar structure of the waver it can be readily straight- 70 ened to assume a fully extended position, free from any kinks or unevenness, notwithstanding long and continued use, thereby not only enabling effective curling or waving while the waver is new but permitting 75 of efficient use for a long time thereafter.

We claim:

1. In a hair waver, a plurality of wires braided together and formed of a plurality of strands. 80

2. In a hair waver, a plurality of wires braided so that the thickness of the braid does not exceed the thickness of substantially two wires thereof, said wires being composed of a plurality of strands, a non-metallic protective covering on said strands, and means for securing the adjacent ends of the wire together. 85

In testimony whereof, we have hereunto set our hands at Oakland, California, this 90 10th day of June, 1920.

HARRY G. HOFFMANN.
GENEVIEVE B. HOFFMANN.

In presence of—
FLOY CRANE.
